UNITED STATES PATENT OFFICE.

GEORGE A. ENSIGN, OF DEFIANCE, OHIO, ASSIGNOR TO THE DEFIANCE MACHINE WORKS, OF DEFIANCE, OHIO, A CORPORATION OF OHIO.

HORIZONTAL BORING-MACHINE.

SPECIFICATION forming part of Letters Patent No. 691,121, dated January 14, 1902.

Application filed September 25, 1901. Serial No. 76,491. (No model.)

To all whom it may concern:

Be it known that I, GEORGE A. ENSIGN, a citizen of the United States, and a resident of Defiance, in the county of Defiance and 5 State of Ohio, have invented a new and Improved Horizontal Boring-Machine, of which the following is a full, clear, and exact description.

The invention relates to woodworking machinery; and its object is to provide a new and improved horizontal wood-boring machine arranged to insure a regular and uniform feed to produce smooth and true holes without the employment of skilled labor or 15 any effort on the part of the attendant of the machine.

The invention consists of novel features and parts and combinations of the same, as will be fully described hereinafter and then 20 pointed out in the claims.

A practical embodiment of the invention is represented in the accompanying drawings, forming a part of this specification, in which similar characters of reference indicate corresponding parts in all the views.

Figure 1 is a perspective view of the improvement arranged for boring spoke-holes in wheel-rims. Fig. 2 is an enlarged plan view of the same with the table for the work 30 removed. Fig. 3 is a longitudinal sectional elevation of the same on the line 3-3 of Fig. 2. Fig. 4 is a cross-section of the same on the line 4-4 of Fig. 2, and Fig. 5 is an enlarged longitudinal sectional elevation of the pneumatic cushion for the spindle.

On the top of a suitably-constructed frame A are arranged bearings B B', in which is mounted to turn a sleeve C, through which extends the feed-spindle D, mounted to slide 40 longitudinally in the said sleeve and rotating therewith. On the forward end of the feed-spindle D is arranged a chuck D' of any approved construction for receiving and holding the bit E, adapted to bore the desired 45 hole into the work F, supported on a suitable table G, held adjustably on the frame A. On the sleeve C, between the bearings B B', is secured a pulley H, over which passes a belt H', extending downwardly and passing over 50 a pulley H², secured on the main shaft I, mounted to rotate in suitable bearings carried

by the frame A, and on the said shaft I are arranged the fast and loose pulleys I', connected with other machinery for imparting a rotary motion to the said main shaft I. The 55 rotary motion of the main shaft I is transmitted by the pulleys H H² and belt H' to the sleeve C, which in turn imparts a rotary motion to the feed-spindle D and the bit E.

In order to feed the feed-spindle D and its 60 bit E forward to move the bit E in engagement with the work F, the following feed mechanism is provided: On the rear end of the feed-spindle D is held loosely a sleeve D², pivotally connected with the fork of a pin J, 65 engaging a socket J', secured to the rear end of an extension K', formed on a rack K, in mesh with a pinion K², secured on a transversely-extending shaft K³, journaled in suitable bearings on the main frame A. A clutch 70 member L is mounted to slide on and rotate with the shaft K³, and the said clutch member L is adapted to be moved in and out of engagement with a clutch member L', mounted to rotate loosely on the outer end of the shaft 75 K³. (See Fig. 4.) The clutch member L' is driven from the main shaft I, and for this purpose the said clutch member L' is formed with a bevel gear-wheel L², in mesh with a bevel-pinion L³, secured on a shaft L⁴, extending 80 longitudinally and journaled in suitable bearings carried by the frame A. On the shaft L⁴ is secured a pulley L⁵, connected by a belt L⁶ with the main shaft I, so that when the latter is rotated a rotary motion is given to 85 the shaft L⁴ by the belt L⁶ and pulley L⁵, and the rotary motion of the shaft L⁴ is transmitted by the pinion L³ and bevel gear-wheel L² to the clutch member L'. When the clutch member L is in mesh with the clutch member 90 L' and the latter is rotated, a rotary motion is transmitted to the shaft K³, which by the pinion K' imparts a sliding motion to the rack K and its extension K' in the direction of the arrow a' to move the feed-spindle D in the 95 same direction to bring the bit E in engagement with the work. It is understood that while this takes place the bit E is rotated by the means above described.

After the hole has been bored to the desired 100 depth the clutch member L is thrown out of mesh with the clutch member L', and in or-

der to impart a quick return movement to the rack K, the feed-spindle D, and its bit E the following device is provided: The forward end of the rack K is pivotally connected by a link N with the upper end of a lever N', fulcrumed at N² on the main frame A, and the lower end of the said lever is connected with a spring N³, attached to a screw-rod N⁴, held adjustably on the frame A to permit of regulating the tension of the spring N³. When the rack K is moved forward in the direction of the arrow a', as above described, a swinging motion is given to the lever N', so that the spring N³ is placed under tension, and as soon as the clutch member L is moved out of engagement with the clutch member L' then the spring-pressed lever N' and its link N impart a quick return movement to the rack K, the feed-spindle D, and the bit E.

20 The movable clutch member L is engaged by a shifting-arm O, secured to a shaft O', extending longitudinally and journaled in suitable bearings carried on the frame A. On the shaft O' is fastened a crank-arm O², pressed on by a spring O³ and pivotally connected by a link O⁴ with a treadle P, fulcrumed on the main frame A and under the control of the attendant's foot. Thus when the treadle P is swung downward the link O⁴ 25 imparts a downward swinging motion to the crank-arm O² against the tension of the spring O³ thereof, and this downward movement of the crank-arm O² causes a turning of the shaft O', so that the shifting-arm O moves the clutch member L in engagement with the clutch member L'. As soon as the attendant releases the pressure on the treadle P the spring O³ returns the several parts to the former position, and in doing so causes the shifting-arm O to move the clutch member L inward and out of mesh with the clutch member L'. From the foregoing it will be seen that as long as the attendant presses the treadle P a forward feeding of the spindle D and its bit E takes place, and as soon as the attendant releases the treadle the spring-pressed lever N' and its link N impart a quick return movement to the rack K, the spindle D, and the bit E without requiring 35 stoppage of the main driving-shaft I, the shaft L⁴, and the sleeve C and spindle D.

40 In order to take up the jar and shock incident to the spindle D moving suddenly back into a rearmost position, I provide a pneumatic cushion, arranged as follows: On the forward end of the sleeve C is secured or formed a head Q, having a cylindrical recess engaged by a piston Q', secured on the spindle D adjacent to the chuck D'. In the head Q is secured a flexible ring Q², preferably made of leather and extending over a number of air-holes Q³, formed in the closed end of the head Q, as plainly illustrated in Fig. 5. When the spindle D is fed forward in the direction of the arrow a', as previously mentioned, the piston Q' moves forward in the head Q, and thereby draws air into the head

through the air-openings Q³ and past the flexible valve Q². As soon as the clutch member L is thrown out of mesh with the clutch member L' and the spindle D is suddenly returned by the action of the spring-pressed lever N' the piston Q' moves against the air in the head Q, and thereby causes closing of the flexible valve Q², so that the air is confined in the head Q, and thereby forms a cushion for the piston Q' and the spindle D. The air is momentarily compressed in the head Q; but the several parts of the cushion are so arranged that this confined and compressed air can readily leak out gradually, however, to permit the piston Q' to finally reach the innermost position in the head Q, as indicated in Fig. 5. From the foregoing it is evident that the forward feeding of the bit E is uniform and gradual to insure true and smooth boring of the holes in the work F, and the return movement of the said bit E is very quick and without shock or jar, so that the parts of the machine are not liable to be thrown out of proper alinement.

Having thus described my invention, I claim as new and desire to secure by Letters Patent—

1. A boring-machine, having a feed mechanism for the spindle, comprising a rack connected with the spindle and mounted to travel in the direction of the spindle, a pinion in mesh with the rack, a pinion-shaft, a movable clutch member mounted to rotate with and to slide on the said pinion-shaft, a driven clutch member adapted to be engaged by the said first-named clutch member, a manually-controlled shifter for the said first-named clutch member, and a spring device for imparting a quick return movement to the rack when the clutch members are disengaged, as set forth.

2. A boring-machine, having a feed mechanism for the spindle, comprising a rack connected with the spindle and mounted to travel in the direction of the spindle, a pinion in mesh with the rack, a spring-pressed lever connected with the rack, a pinion-shaft, a movable clutch member mounted to rotate with and to slide on the said pinion-shaft, a driven clutch member adapted to be engaged by the said first-named clutch member, and a manually-controlled shifter for the said first-named clutch member, comprising a shifter-arm engaging the movable clutch member, a shaft carrying the shifter-arm, a crank-arm on the shaft, and a treadle connected with the said crank-arm, as set forth.

3. A boring-machine, having a feed mechanism for the spindle, comprising a rack connected with the spindle and mounted to travel in the direction of the spindle, a pinion in mesh with the rack, spring-pressed lever connected with the rack, a pinion-shaft, a movable clutch member mounted to rotate with and to slide on the said pinion-shaft, a driven clutch member adapted to be engaged by the said first-named clutch member, and a manually-

- controlled shifter for the said first-named clutch member, comprising a shifter-arm engaging the movable clutch member, a shaft carrying the shifter-arm, a crank-arm on the shaft, a treadle connected with the said crank-arm, and a spring for the shifter to move the movable clutch member out of mesh with the driven clutch member, as set forth. 45
5. A boring-machine having a feed mechanism for the spindle, comprising a rack connected with the feed-spindle, a pinion meshing with the rack, a shaft on which the pinion is mounted, a driving mechanism, means for connecting and disconnecting the driving mechanism with the pinion-shaft, and a spring-pressed device imparting a quick return movement to the rack when the pinion-shaft is disconnected with the driving mechanism, as set forth. 50
6. A boring-machine having a feed mechanism, comprising a rack connected with the feed-spindle, a pinion meshing with the rack, a shaft on which the pinion is mounted, a driving mechanism, means for connecting and disconnecting the driving mechanism with the pinion-shaft, and a spring-pressed lever pivotally connected with the rack, as set forth. 55
7. A boring-machine, having a feed mechanism comprising a rack connected with the feed-spindle, a spring-pressed lever connected with the said rack, a pinion in mesh with the rack, a pinion-shaft, and a clutch mechanism on the said shaft and consisting of a driven clutch member and a movable clutch member rotating with the pinion-shaft and adapted to be moved in and out of gear with the said driven clutch member, as set forth. 60
8. A boring-machine, having a driven sleeve, a feed-spindle mounted to slide in and to rotate with the said sleeve, and a pneumatic cushion for the said spindle and arranged on the sleeve, as set forth. 65
9. A boring-machine, having a driven sleeve, a feed-spindle mounted to turn with and to slide on the said sleeve, means for gradually feeding the feed-spindle forward, means for suddenly returning the feed-spindle, and a pneumatic cushion for the feed-spindle to take up the slack incident to the sudden return movement of the feed-spindle, as set forth. 70
10. A boring-machine, having a pneumatic cushion for the feed-spindle, comprising a head formed with inlet-openings, a piston movable in the head and carried by the feed-spindle, and valves over the said openings to control the ingress and egress of air to the said head at the closed end thereof, as set forth. 75
11. A boring-machine, having a revoluble sleeve formed with a head, a feed-spindle mounted to slide in and to turn with the said sleeve, a piston on the said spindle and fitted in the said head, and a flexible washer in the closed end of the head and extending over air-openings in the said closed end, as set forth. 80
- In testimony whereof I have signed my name to this specification in the presence of two witnesses.
